UNITED STATES PATENT OFFICE.

JOSEPH MOSES WARD KITCHEN, OF EAST ORANGE, NEW JERSEY.

SYSTEM FOR DISTILLATION.

1,008,273.

Specification of Letters Patent.

Patented Nov. 7, 1911.

Application filed May 20, 1907. Serial No. 374,654.

To all whom it may concern:

Be it known that I, JOSEPH MOSES WARD KITCHEN, a citizen of the United States, residing in the city of East Orange, county of Essex, and State of New Jersey, have invented new and useful Improvements in Systems for Distillation, of which the following is a specification.

The object of the invention, which is of special value in the distillation of crude petroleum oil, is to secure economy in the use of fuel; to make the process a continuous one; to prevent the incrustation of coke in the stills; to reduce the amount of fixed 10 gases produced in the distilling process; to reduce the cost of repairs; to economize in the amount of land occupied by the distilling plant; to utilize to the fullest extent the value of the fixed gases necessarily produced 15 in the distilling process through the combined application of the force of the explosion of the gas and the heat generated by the explosion of the gas; and to utilize regeneratively the heat carried from the stills 20 by the various distillates.

In the accompanying drawings: Figure 1 represents a vertical side elevational view of a system containing my invention, it being partly in section and having parts broken 25 away. Fig. 2 is an elevational view of the reverse side of the system shown in Fig. 1, parts being broken away and parts being in section. Fig. 3 is a plan view of the same system, partly in section, on the line 3—3 30 Fig. 1, and parts being broken away. Fig. 4 is a vertical elevation of the same system, partly in section on the line 4—4 Fig. 1, and parts being broken away. Fig. 5 is a detail sectional view of an automatic heat 35 regulator drawn on a larger scale. Fig. 6 is a front view of the regulator shown in Fig. 5.

The reference characters represent the same parts in all the figures, and indicate 40 as follows:

A is an air heating economizer.

A¹ are air tubes.

A² is an outlet for water of condensation.

B are compression tanks.

50 B¹ is a safety valve.

C is a combustion chamber.

C¹ is the wall of the building inclosing the system.

C² is the roof of the building.

55 C³, C⁴, and C⁵ are heat diluting and gas admixing compartments.

D is a device for admitting air for reducing the temperature of hot gases.

D¹ is an automatic device for further regulating the temperature of gases.

60 D² are emergency dampers for the exit of hot gases.

D³ are gas apertures or passages.

D⁴ is an air slide.

D⁵ is a handle for actuating the slide D⁴.

E is an internal combustion engine.

E¹ is a discharge pipe for exhaust engine gases.

F is an engine for pumping water.

F¹ is a force pump.

G is a grate.

G¹ are air twyers for introducing under-grate air for combustion.

G² are over-fire apertures for air for combustion.

H are conduits for volatilized vapors.

I is a condenser for the first distillate.

I¹ is a condenser for the second distillate.

I² is a condenser for a third distillate.

J is an economizer for cooling tarry residue and for producing steam.

J¹ is a tar conduit.

K is a waste gas stack.

K¹ is a chimney flue.

L is a rotary blower.

85 L¹ are warm air conduits.

L² is a conduit for compressed air.

L³ is a damper for controlling over-fire air introduction.

L⁴ is a damper for controlling the introduction of air underneath the grate G.

M indicates a fan motor.

M¹ is an induction fan for inducing a draft.

M² is a rotary pump for pumping crude oil.

N are connecting and inter-communicating oil pipes.

N¹ are heating pipes.

N² are headers.

100 O is an oil tank.

O¹ is a pipe for conveying oil to the still S.

O² is an automatic valve.

O³ is an oil supply pipe.

P is a pump for compressing steam mechanically.

Q are air diluting passages for adjunct control of gas temperatures.

Q¹ are air apertures.

Q² are slides for the air diluter Q.

R is a shaft.

R¹ is a spiral thermostat.

- R² is a motor arm.
 R³ is an anti-friction wheel.
 R⁴ is a lid.
 R⁵ is a counter-weight.
 5 R⁶ is a hinge shaft.
 R⁷ is a handle for actuating the emergency dampers D².
 S is the primary still for producing naphtha products.
 10 S¹ is a secondary still.
 S² is the third still.
 S³ are intermediate gas passages.
 T is a tar cleaning tank.
 T¹ are explosion and vapor outlets.
 15 U is a steam main.
 U¹ is a waste steam conduit.
 U² are outlets from the steam main.
 U³ are the steam conduits leading from the condensers and the economizer J.
 20 V is a water pipe.
 V¹ is a by-pass pipe for warmed water.
 W represents masonry walls.
 X are distillate outlets.
 Y is a coal car.
 25 Z is an overflow pipe for tar residue.
 The principles applied to this distilling system are: first: to secure a relatively perfect and complete combustion of the fuel used. Second: to dilute the heat of the 30 gaseous products of combustion with air after combustion has been perfected, for reducing the temperature of the gases effecting the distilling process to a point (say about 700 degrees F.) that will prevent the 35 formation of coke incrustations in the stills. Third: to apply the heat thus diluted or reduced to the oil progressively, gradually losing the heat of the gases to the oil and progressively heating the oil; the oil and 40 the heating gases being brought appositely in contact with the intermediary heating surfaces in counter-currents. Fourth: when applying the counter-current principle, to use the vertical counter-current; the heating 45 gases being conveyed from a high level of the stills to a low level, and the oil being conveyed through the stills from a low level in upwardly traveling, divided currents. Fifth: to use in the system a battery of as 50 many separate stills as there are distillates wanted, each still having sufficient heating surface to produce the proportional amount of distillate desired from the total bulk of the oil treated. Sixth: to utilize an induced 55 draft, mechanically produced, throughout the whole system, from and including the furnace, and extending through all the heating and intermediate gas conveying cavities of the system. Seventh: to provide for 60 each still a separate condenser, and to economize the heat of each distillate by forming steam in each individual condenser. Eighth: to utilize the steam thus generated by producing it at a low pressure and giving it a 65 strong expansive pressure through mechani-

cal compression, by the intense force of gas explosion, and then to use the steam thus mechanically compressed in those places in which it can be advantageously utilized.

The furnace here shown is designed to 70 use fine coal dust; and is hand fired. There are several furnaces in the system, so that the grate which pertains to either of the furnaces may be cleaned while the other grates may continue to burn fuel producing heat 75 enough to keep up a continuous distillation in the system. Each furnace has a controlled air supply, both above and below the fuel mass. (See dampers L³ and L⁴ which control the admission of air through the 80 apertures G¹ and G².)

As I economize heat in many ways in this system, I save much of the heat of radiation and some hydro-carbon vapors, by inclosing the system in a building C¹, and by making the roof of this building impervious to the upward exit of warm air and volatilized gases; and also by making the roof C² of thin metallic sheeting, much of the sun's heat can be transmitted through the 90 roof. Heated air and also ill smelling hydrocarbon vapors that would otherwise contaminate the atmosphere of the neighborhood, are thus collected and held in the concavity below the roof of the building, I 95 draw air and hydrocarbon vapors for combustion from an upper level near the apex of the roof of the building, through the air conductor L¹, by means of the rotary fan L. I also use the heat of waste steam and of 100 water of condensation to heat air for combustion, by drawing air through the piping A¹ which runs vertically through the economizer A, into which waste steam is introduced at a high level; and in which water 105 of condensation collects in the lower part of the economizer. As air is drawn from below upward through the economizer A, it is primarily heated in its travel by the water of condensation, and then is further heated 110 by the exhaust steam in the upper part of the economizer. The air thus heated along with the warmed air from the top of the building is passed by the fan L through the conduit L² to the various furnaces. Any 115 superfluity of waste steam that is not condensed in the economizer A is discharged through the pipe U¹ Fig. 3 into the upper part of the combustion chamber C, helping to dilute the temperature of the heating 120 gases, and adding to the sum total of the heat absorbed in the stills of the system. Any waste gas from the engine E is also economized in the same way by being discharged into the conduit U¹ from the engine 125 E through the pipe E¹, which is broken for clearness. As the gases rise in the combustion chamber C they are diluted with air through the tubes D just before the gases are passed through the apertures D³. The 130

entrance of air through the tubes D is controlled by the air slide D⁴ actuated by the handle D⁵. In order to prevent too high a temperature in the heating gases, and also to get a proper admixture of the gases with air, the superimposed compartments C³, C⁴ and C⁵, are provided, and which are divided from each other by masonry arches or baffles covered with ashes which prevents direct upward convection of heat. The gases having to pass through the apertures D⁸ successively from one side of the compartments to the other, the gases and air are well admixed before they reach the top of the still S². To obviate any oversight on the part of the attendants, the automatic temperature regulator or thermostat D¹ is provided (see Fig. 5). By means of the spiral R¹ the shaft R is rotated by increases of temperature, and if the temperature becomes too high the arm R¹ pushes the wheel R⁸ against the lid R⁴, allowing cool air to enter the compartment C³. The lid R⁴ is hinged on the shaft R⁹, and each lid has a counter weight R⁵. Slight pressure is all that is necessary for the action of the spiral R¹ to open the lids and allow cool air to enter. As a further prevention from overheating the oil in the battery of stills in the system, I provide the emergency dampers D² at the top of the compartment C⁶. These can be manipulated by hand, and if the temperature of the gases is too high, the gases can find exit through the apertures controlled by the dampers D² at the top of the compartment C⁶.

The induced draft acting through the system is effected by the induction fan M¹ actuated by the steam turbine-motor M. The induction fan M¹ draws the gases through the system and through the chimney flue K¹, and expels them through the gas stack K. There are two such fans and stacks for the system. I use, for a further control of the temperature acting on each still of the battery after the gases have passed the still S², air introduced through the passages Q and air apertures Q¹ which are controlled by the slides Q². The air coming from the heating cavity of one still can thus have its temperature reduced if necessary in its travel upward through an intermediate space between each still and before being applied to the next still of the battery. The travel of the gases under the influence of the induction fans is as follows: After passing from the furnace and through the compartments C³, C⁴ and C⁵, they pass into the cavity containing the still S² at the top of the cavity, and pass down to the bottom of that cavity, then up through an intermediate gas passage S³ into the top of the cavity containing the still S¹, and downward through that cavity, and so on until they have passed through all the still cavities

in the system, and are finally expelled through the stacks K. In practice, the heating gases would be applied to the heating surfaces of the still S² at a temperature of about 700° F, then applied to the top of the still S¹ at about 500° F, and finally be applied to the top of the still S at about 300° F. By regulating the intensity of the rate of combustion in the furnaces proportionately to the extent of the heating surface provided in the battery of stills, all the heat generated in the furnaces or introduced above the furnaces, can be utilized by having it absorbed into the oil in the travel of divided currents of the oil through the several stills in contra-current to the travel of the heating gases.

I utilize the heat of the several distillates driven off from the several stills, by carrying each distillate through a separate condenser. I is the condenser for the still S, I¹ is the condenser for the still S¹, and I² is the condenser for the still S². Cold water for condensing is forced by the pump F¹ actuated by the engine F through the water-main V into the bottom of each condenser and also into the bottom of the economizer J which cools the residual tarry product overflowing from the still S² through the pipe Z. There are valved connections V¹ connecting the several condensers, and the tar cooler J, so arranged that some of the warmed water in any condenser may be conveyed to the next one. Inasmuch as the distillate carrying off heat from each successive still carries a greater amount of heat than that from the preceding still, it is evident that water of a progressively increasing temperature will condense distillates of progressively increased temperatures. The vapor of each distillate is introduced at the top of the special condenser provided for it and passes downward through vertically disposed piping in contra-current to the condensing water that travels upward in each condenser, which water is gradually heated in its upward travel; and before arriving at the top begins to emit steam. The residual tarry matter from the still S² is conveyed into the top of the cooler and economizer J and travels downwardly, heating water and producing steam. The steam produced in all the condensers and in the economizer J, are conveyed by the pipe U³ Fig. 3 to the steam compressing pump P which is actuated by the internal combustion engine E. This engine uses as fuel the fixed gases that are produced in the system. Previously this fixed gas has usually been burned under the stills; but I first utilize its explosive force to exhaust the steam from the condensers and the economizer J, and to mechanically give great pressure to the steam and then use the heat of the explosion as an adjunct means of heating the stills. The

mechanically compressed steam is forced into the storage tank B under a high working pressure, from which tank it may be drawn for work through the steam main U 5 and branches U². Safety valves B¹ allow any excess of steam to escape into the air heater A; air for combustion passing up through the pipes A¹ and absorbing the heat of this steam. The tarry residue which 10 is cooled by passing down through the economizer J is conveyed through the pipe J¹ into the tanks T in which it is treated with acid, and after sedimentation of the impurities in the tar, which are precipitated by 15 the acid, the cleaned residue is removed for further treatment in the production of lubricating oils and paraffin.

The drawings here presented indicate the application of my invention to the primary 20 distillation of crude oil only; but the same principles may be applied to further processes in connection with the treatment of petroleum oils in securing their purification from sulfur compounds, and in other distilling and refining processes. This method 25 of distillation can also be used in connection with the treatment of products other than petroleum oils.

What I claim as new is:

30 1. In a distilling system, the combination of (1) a plurality or battery of stills, (2) a furnace for producing heating gases for said stills, (3) means for reducing the heating gases to a temperature that will not cause coke incrustation in said stills, and (4) means for the mechanical induction of a draft through said battery or plurality of stills and said furnace, said draft drawing heating gases through said furnace and 35 progressively through said battery of stills and over the heating surfaces of said stills to and for delivering said gases into the waste stack of said system.

2. In a distilling system, the combination 45 of (1) a battery of stills, (2) a furnace for generating heating gases for the direct heating of said stills with said gases, (3) means for inducing a draft through said system, first through said furnace and then drawing 50 the gases generated in said furnace successively over each of the stills in said system, said battery of stills being arranged between said furnace and said induction means, said stills being located separately in individual 55 heating cavities and comprising vertically disposed tubing connecting at the top and communicating with a chamber head for the disengagement of distilled vapors, and connected at the bottom with means for conveying oil into said vertically disposed tubing, (4) an oil reservoir for supplying oil 60 continuously to said stills, (5) piping for the conveyance of oil, connecting said reservoir with the still of said system requiring 65 the application of the least heat, and pro-

viding for the flow of said oil from said reservoir to the bottom of said last named still, said piping providing for conveying an overflow from the top of each still to the bottom of another still and thus on in series 70 through all the stills of said system, and (6) means for regulating the degree of heat applied to each still and for progressively losing heat to each still from the gases generated in said furnace, for securing successive 75 fractionates from the several stills of the system.

3. In a distilling system, the combination with a plurality or series of stills, of (1) a furnace for producing heat for heating the 80 stills of said system with the hot gases generated in said furnace, (2) means for conveying said heat to said plurality of stills and for losing said heat in the travel of the 85 heating gases through absorption of said heat in decreasing amounts to each successive still, each of said stills providing heating surfaces for the fractional volatilization of a separate distillate from each still, (3) condensers for each still, comprising means 90 for producing steam from the condensation of the distillates passed into each of said condensers, and (4) means for conveying the steam produced in all of said condensers to a place for use in said system. 95

4. In a distilling system, the combination with a still producing oil distillates and fixed gases, of (1) an internal combustion engine for generating power from the fixed gases produced in said system, (2) a pump 100 actuated by said internal combustion engine for the mechanical compression of the steam generated in said system, (3) means for producing from the condensation of distillates and conveying steam to said pump and for utilizing said steam after it has been mechanically compressed by said pump in the motors connected with said system and for combustion processes and heating in said system, (4) means for conserving the waste heat of said engine in heating air for combustion and in improving the combustion process for heat generation and for heat application to said still, and (5) means for collecting and conveying to said engine for 110 explosive use in said engine the fixed gases produced in said still. 115

5. In a distilling system, the combination with a heating furnace and a battery of stills, of (1) means for producing steam from distillates, (2) an economizer, said economizer being constructed and disposed to receive exhaust steam or superfluous steam in the upper levels of said economizer, and for holding a body of water of condensation in the lower part of said economizer, and having vertically disposed tubes for conveying air through said tubes in an upward travel, first through said water of condensation, and second through said steam, and for 125 130

the outflow of said air after being heated in said economizer, (3) means for conveying said air when heated by said steam into said furnace for air for combustion, and (4) means for conveying any superfluity of steam from said economizer into the combustion chamber of said furnace.

6. In a distilling system, the combination with the stills of said system of (1) a furnace comprising a combustion chamber, (2) contracted orifices or apertures for the emission of gaseous products from said chamber, (3) air inlets for conveying cold air and admixing said cold air with hot gaseous products of combustion at or about where the gaseous products leave said chamber, (4) means for controlling the admission of air thus introduced, said means being mechanically and automatically actuated, (5) other means for controlling the temperature of the gases applied in said system, after primary application of said heat, (6) means for diverting and entirely preventing the contact of too hot gases with the heating surfaces of said system, (7) means for controlling the amount of heat desirable to be applied to each of the stills comprised in said system, and (8) said stills.

7. In a distilling apparatus, the combination of (1) means for developing heating gases for distilling, (2) means for reducing the temperature of the heating gases generated after their production, to a temperature that will not cause coke incrustation in the stills of said apparatus before applying said heat to the surface of a still, (3) a battery of stills, (4) means for applying the diluted heat successively to the units of said battery of stills with the application of a lessened degree of heat to each successive still, and (5) means located between each still and its successor for controlling the temperature applied to each successive still.

8. In a distilling system, the combination of (1) a furnace for generating heating gases for heating a battery of stills, (2) said battery of stills, (3) means for inducing a draft through said furnace and over the heating surfaces of the stills of said battery, (4) means for securing a proper temperature in the heating gases generated in said furnace before said gases have contact with said battery of stills to prevent the formation of coke incrustations in said stills and for the application of appropriate degrees of heat to each still of said battery, (5) means for condensing separately the distillate of each still of said battery, and for producing steam from the heat of each distillate, (6) means for mechanically compressing and adding expansive force to said steam and for utilizing said steam when compressed for actuating the motors in said system and for heating uses in said system, (7) means for heating air for combustion with

exhaust steam and water of condensation and for using said warmed air economically in combustion processes and heating in said system, (8) means for utilizing the heat of radiation in said system for securing economy in combustion in said furnace, and (9) means for securing a continuous supply of oil to said stills and a continuous distillation of said oil in said system.

9. In a distilling system, the combination of a furnace, a still, and a draft inducer, said still having means for passing heating gases from said furnace in a current from the top to the bottom of said still and for passing a fluid for distillation from a low level to a high level in said still in counter-current to the travel of the gases through said still, said draft inducer being for the creation of an induced draft through said furnace and over the heating surfaces of said still by inducing a plunging draft over the heating surfaces of said still.

10. In a distilling system, the combination of (1) a plurality of stills for the successive repeated distillation of distillates of progressively increasing specific gravity from a crude hydrocarbon oil, (2) a cooling receptacle or tank for receiving tarry residue from said stills and means for conveying said residue as an overflow from said stills into said tank at a high level in said tank and for a downward travel of said residue through said tank and for drawing said residue from said tank at a low lever, (3) means in said tank for conveying water therethrough from a low level to a high level in counter-current to the flow of tarry residue through said tank and for forming steam by the conveyance of the heat of said tarry residue to said water, and (4) means for uniting said steam with other steam formed in said system and for conveying said steam to place for use in said system, said tank being separate and apart from the condensers of said system.

11. In a distilling system, the combination of (1) a battery of stills comprising means for the repeated distillation of a distillable substance and for the successive creation of distillates of progressively increasing specific gravities, (2) a battery of condensers providing a separate condenser for each of the stills in said battery of stills, said condensers being constructed and disposed to receive vaporized distillates at a high level of said condensers and for conveying said vapors in a downward travel through said condensers and for conveying the condensed vapors out through a low level exit of said condensers, (3) means for drawing partially warmed water from a relatively high level of one condenser and for forcing said water into the bottom of the condenser next in the series of said battery of condensers, for condensing a distil-

late of a higher temperature than that of the distillate in the first named condenser, said condensers being located at a uniform level, said condensers comprising means for the upward travel of water in said condensers and having exits for the emission of steam at or near the top of said condenser, and (4) means for uniting the steam formed in all of said condensers and for conveying said steam to a place of use.

12. In a distilling system the combination of (1) an oil still for refining oil, (2) means comprising a furnace and combustion chamber for effecting a substantially complete combustion of fuel for heating said still, said means also comprising means for air feeding the fuel through and above the fuel mass, (3) means for reducing the temperature of the hot gaseous products of combustion after the combustion of the gases, but before said gases have contact with the heating surfaces of said still, to a degree that will not cause burning of the oil and consequent incrustation with coke from the burned oil in said still, of the surfaces of said still, said last named means being separate and apart from the air feeding means effecting combustion, and (4) means for applying the reduced heat of the gases to said still.

13. In a distilling system, the combination of (1) a still for distilling and refining oil, (2) a furnace comprising a combustion chamber for generating hot gaseous products of combustion for heating said still, and (3) means for automatically reducing the temperature of the gaseous products of combustion to a temperature desirable to be applied to said still, said means comprising a mechanism operating automatically for admixing cool air with said gaseous products of combustion after said gaseous products of combustion are completely formed, but before the gaseous products of combustion are applied to said still, said mechanism comprising means for actuating the mechanism through the expansion by heat of parts of said named mechanism.

14. In a distilling system, the combination of (1) a still, (2) means for generating hot gaseous products of combustion for heating said still, (3) means for automatically mixing cool air with the burned gaseous products of combustion from said first

named means for reducing the temperature and controlling the temperature of the gases applied to said still, and (4) means including a relief valve for by-passing over heated gaseous products of combustion before said gases have contact with said still.

15. The combination of (1) means for generating a combustible gas, (2) means for accurately burning the gas with a definite amount of air mechanically admixed with the gas, (3) means for accurately diluting the gaseous products of combustion with a cool gas to secure a temperature in the burned gases that when applied to a still for distilling hydro-carbon oils will not carbonize the oils in said still, and (4) said still for distilling the oil, said still being heated by said gases of reduced temperature.

16. The combination of (1) a still for distilling hydro-carbon oil, said still being constructed and disposed for the vertical counter-current travel of the heating gases and the oil to be heated, the gases traveling downwardly over the heating surfaces of the still, and the oil traveling upwardly in the still, (2) a furnace for generating heat for heating the stills, (3) means for securing the complete combustion of the fuel used in said furnace through a positive control of the air used in burning said fuel, (5) means for accurately diluting the gaseous products of combustion from said furnace with a cool gas and for applying said gas controlled in temperature to said still for heating said still.

17. The combination with a still of (1) means for generating a combustible gas, (2) means for securing a substantially complete burning of the gas with accurately supplied amounts of air mechanically admixed with the gas, (3) means for accurately and automatically diluting the gaseous products of combustion with cool air for controlling the temperature of the gas applied to said still, and (4) means for inducing a mechanically produced draft of the heating gases controlled in temperature over the heating surfaces of the still.

Signed at New York, N. Y., this 17th day of May 1907.
